FIG. 1.

FIG. 2.

Fig. 3.

Fig. 4.

FIG. 1 is a perspective view of the front of a portable record changer or similar article showing our new design with the record changer and speakers in closed position; FIG. 2 is a rear perspective view of the portable record changer, with the parts positioned as in FIG. 1;

FIG. 3 is a front elevational view with the speakers in one open position and the record changer upright; FIG. 4 is a front elevational view with the speakers fully open and the record changer in playing position; FIG. 5 is a top plan view of FIG. 4; and

FIG. 6 is a side elevational view, looking toward the left of FIG. 5.

The dominant features of our design reside in the portion shown in full lines.

The grille, fragmentarily shown in FIGS. 3 and 4, is continuous within the boundaries, as indicated.

We claim:

The ornamental design for a portable record changer or similar article, substantially as shown and described.
